(57) **CLAIM**

The ornamental design for an inline conduit coupling, as shown and described.

DESCRIPTION

FIG. 1 is a left perspective view of an inline conduit coupling of the present invention;

FIG. 2 is a top plan view of the inline conduit coupling of FIG. 1;

FIG. 3 is a front elevational view of the inline conduit of FIG. 1;

FIG. 4 is a rear elevational view of the inline conduit coupling of FIG. 1;

FIG. 5 is a left side view of the inline conduit coupling of FIG. 1, the right side view being similar thereto; and,

FIG. 6 is a bottom plan view of the inline conduit coupling of FIG. 1.

The matter shown in phantom lines in FIG. 1 is for illustrative purposes only, and forms no part of the claimed design.

1 Claim, 3 Drawing Sheets
